MACHINE FOR TREATING SHOE WELTS

Filed May 20, 1935

UNITED STATES PATENT OFFICE

2,069,748

MACHINE FOR TREATING SHOE WELTS

Charles G. Brostrom, Peabody, Mass., assignor
to United Shoe Machinery Corporation, Paterson, N. J., a corporation of New Jersey

Application May 20, 1935, Serial No. 22,364

6 Claims. (Cl. 69—1)

This invention relates to machines for treating the welts of welt shoes to prepare them, for example, for the reception of adhesive for securing outsoles to the shoes. As herein illustrated the invention is embodied in a machine for roughing a surface of the welt and the adjacent trimmed edges of the inseamed materials of a welt shoe preparatory to coating those parts with cement for attaching an outsole to the shoe.

Such machines commonly employ a rotary roughing tool and a welt support arranged to support the work against the thrust of the tool, as well as to guide the shoe and aid the operator in controlling it so as to produce accurate roughing. A machine of this character is disclosed and claimed in United States Letters Patent No. 2,008,059, granted July 16, 1935, upon my copending application Serial No. 602,467, filed April 1, 1932, and it is an important object of the present invention to provide an improved welt support for machines of that type, although it should be understood that the invention is not limited to its application to the specific machine mentioned but is capable of embodiment in other machines wherein the work supporting requirements are similar.

In a welt roughing machine employing a rotary roughing tool, which ordinarily runs continuously, it is necessary to withdraw the welt support to a sufficient distance from the periphery of the tool to permit the insertion of the work, which must then be brought into engagement with the tool by movement of the welt support toward the latter. A feature of the present invention consists in the combination with a rotary roughing tool of means for supporting the welt of the shoe against the thrust of the tool and means for moving the supporting means radially of the tool.

This movement of the welt support radially of the tool is advantageous in that it causes the welt of the shoe to be presented accurately to the tool in the best possible manner and the invention also includes provision for adjustment of the extent of this radial movement, to determine exactly the depth to which the material of the welt shall be roughened.

It is very convenient for the operator to be able to change the position of the welt support in order to enable him to hold the shoe at the angle which will best enable him to see clearly how the work is progressing, and another feature of the invention consists in so mounting the welt support that it is readily adjustable in position circumferentially of the rotary roughing tool without disturbing any other adjustments. In the

illustrated machine this is accomplished by mounting the welt support in a carrier block which is supported rotatably upon a stationary sleeve surrounding the tool shaft. By securing the welt support in a carrier slide guided in the block for movement transverse to the axis of the sleeve, the radial movability of the welt support is not disturbed by the circumferential adjustment which changes its angular position around the tool.

These and other features of the invention, relating to adjustments of the welt support around its own axis and also axially of the tool shaft, will best be understood and appreciated from reading the following detailed description of one embodiment of the invention in connection with the accompanying drawing, in which—

Fig. 1 is an angular view of the head portion of a roughing machine equipped with a welt support embodying the invention;

Fig. 2 is a view in side elevation of a portion of the welt-supporting mechanism; and

Fig. 3 is a detail view illustrating the position of the work while it is being operated upon.

The illustrated embodiment of the invention is shown as applied to a machine having the general structure of the machine disclosed in United States Letters Patent No. 1,989,073, granted January 29, 1935, upon my application.

In the drawing, 10 indicates the machine head, 30 which is supported upon a pedestal 12 and has a bearing 14 in which runs a shaft 16 upon the projecting end of which is mounted a roughing tool 18. The shaft 16 is reduced in diameter and threaded at 20 for the adjusting nut 22 and the check nut 24 by which adjustments of the roughing tool may be made, as described in detail in my prior patent.

Upon the rods 26, 28 which are secured in the machine head 10 in parallel relation to the tool shaft 16, is slidably mounted a bracket 30 which may be secured to the rod 28 by a set screw 32 at any desired position of adjustment. The sliding mounting of the bracket 30 upon the two rods 26, 28 permits the bracket to be adjusted longitudinally of the tool shaft 16 but does not permit the bracket to rotate relatively to the shaft.

A normally stationary, horizontal, cylindrical sleeve 34, which is integral with the bracket 30, loosely surrounds the shaft 16, which rotates freely within the sleeve. A carrier block 36 is supported by the sleeve 34, the block being fitted closely to the outside of the sleeve but being rotatably adjustable upon the sleeve about the axis of the tool shaft 16. A set screw 38, threaded

through the block 36 and bearing upon the sleeve 34 permits the block to be secured firmly to the stationary sleeve in any desired position of angular adjustment about the axis of the tool shaft.

5   Mounted in the block 36 is a carrier slide 40 which is reciprocable, in guides 42 formed in the block 36, in a path transverse to the axis of the sleeve 34 and the shaft 16, and approximately tangential to the periphery of the tool 18, although at a substantial distance to one side thereof.

10   Pivoted to a lug 44 projecting from the lower end of the carrier slide 40 is a connecting link 46 which is also connected to a lever 48 movable about a pivot 50 mounted in the lower end of an arm 52 which projects downward from the carrier block 36. The lever 48 is connected at 54 to a rod 56 which extends downward to a manually operable treadle, not shown. A pull spring 58, 15 the lower end of which is connected to the lever 48 and the upper end of which is secured to the arm 52, acts to move the slide 40 upward when it is not depressed by pulling down upon the treadle rod 56.

20   25   The upper limit of movement of the slide 40 is adjustably determined by a stop screw 60 threaded through a bracket 62 extending upward from the carrier block 36, the adjustment of the screw 60 being preserved by a lock nut 64.

30   35   30   Mounted in the lower portion of the slide 40 is an adjustable cross slide 66 having an upstanding portion 68 notched to engage in an annular groove 70 formed in the shank of an adjusting screw 72 which is threaded into the slide 40. A binding screw 74 which is movable in a transverse slot 76 in the slide 40 and is threaded into the cross slide 66, provides for locking the latter in any position of transverse adjustment.

40   45   Extending rearward from the cross slide 66 is a bracket 78 which ends in a split clamp 80 arranged to be tightened by a screw 82 to hold firmly in a horizontal position the cylindrical shank portion 84 of a welt support 86. By loosening the screw 82 the welt support may be freed to permit it to be adjusted angularly about the axis of its shank portion 84 and longitudinally of its said shank portion, across the face of the roughing tool 18. The welt-supporting portion of the member 86 is flattened and made thin so that it 50 can be inserted in the welt crease of a shoe, as illustrated in Fig. 3, wherein 88 indicates the welt, 90 the upper, 92 the insole, and 94 the inseam of a shoe mounted upon a last 96. The work-engaging edge of the flattened welt-supporting member 86 is rounded as shown in Fig. 1 to permit the shoe to be swung around and presented with the edge of its welt at any desired angle to the roughing tool.

55   60   Adjustably mounted upon the shank 84 of the welt support is a finger hold 98 which is split and secured in the desired position by a clamping screw 100.

65   It will be noted that my improved welt-supporting apparatus is so constructed and arranged that any adjustment of the welt-supporting member that could be desired can be effected simply and quickly in a single adjusting operation. Thus the welt-supporting member can be 70 adjusted angularly in a circular path around the circumference of the roughing tool in order to enable the operator to hold the shoe at the angle which will best enable him to see clearly how the work is progressing without disturbing any other adjustment. By adjustment of the stop screw 60

75   the limit to which the welt support may move transversely of the axis of the tool in pressing the welt against the roughing tool can be exactly determined and the depth of the roughing can thus be accurately controlled. By adjusting the cross slide 66 the position of the welt support axially of the roughing tool can be micrometrically regulated and the angular position of the welt support about its own axis can be varied as desired by loosening the clamping screw 82 and turning the member 86, which, at this time, is also free to be moved longitudinally for a rough adjustment. The whole apparatus can be moved longitudinally of the roughing tool shaft to the most advantageous position by loosening the set screw 32.

80   In use the operator depresses the treadle rod 56, with the result that the welt support 86 is moved radially away from the tool 18 a sufficient distance to permit the welt to be inserted. Upon release of the treadle the spring 58 causes the work to be pressed against the continuously running roughing tool and the roughing action proceeds as the welt of the shoe is moved along over the welt support. Inasmuch as the line of movement of the carrier slide 40 is approximately parallel to that radius of the roughing tool which passes through the welt support 86 the work is pressed normally against the tool to permit the tool to operate most advantageously thereon. 30

85   Having described the invention, what is claimed as new and is desired to be secured by Letters Patent of the United States is:

1. In a machine for roughing the welt of a welt shoe, the combination with a rotary roughing tool of means for supporting the welt of the shoe against the thrust of said tool, means tending to move the supporting means radially of the tool toward the tool, and manually operated means for moving the supporting means away from the tool. 35

2. In a machine for roughing the welt of a welt shoe, the combination with a rotary roughing tool of a welt support adapted to enter the welt crease of the shoe and support the welt against the thrust of said tool, said welt support being independently adjustable in position both radially and circumferentially of the tool, spring means for urging the welt support toward the tool, and manual means for retracting the support against the tension of the spring. 50

3. In a machine for roughing the welt of a welt shoe, the combination with a rotary roughing tool of a welt support adapted to enter the welt crease of the shoe and support the welt against the thrust of said tool, said welt support being independently adjustable in position radially, circumferentially and axially of the tool, spring means for urging the welt support toward the tool, and manual means for retracting the support against the tension of the spring. 55

4. In a machine for roughing the welt of a welt shoe, the combination with a rotary roughing tool of a welt support guided for movement radially of the tool, means for adjustably limiting movement of the welt support toward the tool, and manually operable means for moving said support away from the tool to permit the insertion of the welt between the support and the tool. 70

5. In a machine for treating the welt of a welt shoe, the combination with a rotary tool of a carrier slide guided for movement in a path at one side of, and approximately tangential to, the tool, and a welt support mounted in the slide 75

and disposed substantially in the radial line of the tool which is parallel to said path.

6. In a machine for treating the welt of a welt shoe, the combination with a rotary tool of a welt support having a straight cylindrical shank portion, a thin, flattened end portion in line with said shank portion and presenting a

welt supporting surface facing the periphery of the tool, and a carrier in which said shank portion is mounted for rotary adjustment around its own axis to vary the angle of the welt supporting surface to the periphery of the tool without bodily movement of the welt support. 5
